UNITED STATES PATENT OFFICE

EDWIN I. FARNSWORTH, OF LEAVENWORTH, KANSAS.

IMPROVEMENT IN IRON BRIDGES.

Specification forming part of Letters Patent No. **159,084**, dated January 26, 1875; application filed January 4, 1875.

To all whom it may concern:

Be it known that I, EDWIN I. FARNSWORTH, of Leavenworth, in the county of Leavenworth and State of Kansas, have invented a new and useful Improvement in Bridges, of which the following is a specification:

My invention consists of an improved construction of girder or arch for railroad and other bridges, of two vertical (edgewise) channel or **I**-beams, with a flat plate riveted on top, transverse plates under side at the posts and feet of the arch, and diagonal or lattice bracing intermediate to the transverse plates, which affords greater strength for resisting the crushing effect on the feet of the arch where the greatest strain exists, and also greater lateral strength along the arch, which is very essential in this form of truss. It also enables the inside of the arch to be painted.

Figure 1 is a side elevation of an arch constructed according to my invention, some parts being sectioned. Fig. 2 is a plan of the under side of the arch, and Fig. 3 is a transverse section on line *x x* of Fig. 1.

Similar letters of reference indicate corresponding parts.

A represents the two vertical beams, which, in this case, are made of what is known as channel-beams, but may be of the **I**-beam form, if preferred. B is the plate, riveted on the top; C, the transverse plates on the under side at the posts and the feet of the arch; and D represents the diagonal lattice-braces intermediate to the transverse plates, all as clearly represented in the drawings.

Having thus described my invention, what I claim as new, and desire to secure by Letters Patent, is—

The combination, in an arch for bridges, of channel or **I**-beams A, top plate B, transverse plates C, and diagonal intermediate braces D, substantially as specified.

EDWIN I. FARNSWORTH.
